UNITED STATES PATENT OFFICE

2,661,139

CONSUMER TYPE CONTAINER

Lewis C. Brooks, Milwaukee, Wis., assignor of one-third to Ira Milton Jones, Milwaukee, Wis.

Application February 10, 1950, Serial No. 143,423

6 Claims. (Cl. 229—23)

1

This invention relates to consumer type containers and refers particularly to containers made of fiber or paper board and provided with a reclosable cover.

In the production of consumer type containers of fiber or paper board the problem of providing adequate rigidity for the mouth or open top of the container and at the same time having the opening unrestricted without sacrificing neat appearance and entailing high production costs has perplexed the industry for quite some time. In Patent No. 2,398,404, issued to the applicant April 16, 1946, consumer type containers are illustrated in which the open upper end of the container body has increased strength and rigidity afforded by a simple inexpensive shouldered construction but in this case the reinforcement either partially obstructs the opening or the construction is such that the incorporation of a reclosable cover is impractical and too costly for many products which require a full sized opening as, for instance, soda crackers and cigarettes.

One of the purposes of this invention, therefore, is to provide an improved container of the character described in which ample strength and rigidity are provided for the mouth of the container by a novel, inexpensive neck construction with which the reclosable cover has telescoping engagement.

Another purpose and object of this invention is to provide a container of the character described which is so designed and constructed that both its end closures, that is, its bottom and its cover, may be made or formed over an internal support.

Another object of this invention is to so construct the body and cover of the container that the flanges on the cover which fit over the neck are formed simultaneously with the body blank so that the cover flanges will be absolutely flush with the front and side walls of the container.

Another object of this invention is to provide a container of the conventional one piece carton type with a neck at its open top and a reclosable hinged cover adapted to have telescoping engagement with the neck.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several

2

complete examples of the physical embodiments of the invention constructed according to the best modes so far devised for the practical application of the principles thereof, and in which:

5 Figure 1 is a perspective view of a container embodying this invention, said view showing the cover of the container open;

Figure 2 is a perspective view of the container shown in Figure 1 but with the cover closed and partially sealed;

10 Figure 3 is an enlarged detail sectional view, in perspective, through Figure 1 on the plane of the line 3—3;

Figure 4 is a perspective view of the unit or 15 piece from which the back, bottom and cover of the container shown in Figure 1 are formed;

Figure 5 is a perspective view of the formed-up piece or unit comprising the front and side walls of said container;

20 Figure 6 is a plan view of the blank which produces the back, bottom and cover forming unit shown in Figure 4;

Figure 7 is a plan view of the blank which produces the front and side wall unit shown in Figure 5;

25 Figure 8 is a perspective view with parts broken away and in section, illustrating another modification of this invention;

Figure 9 is a perspective view showing the two 30 pieces from which the back, bottom and cover flanges of the container shown in Figure 8 are formed; and

Figure 10 is a plan view of the so-called body blank for the container shown in Figure 8 and illustrating particularly the manner in which the cover flanges are formed concomitantly with the formation of the body blank.

Referring now particularly to the accompanying drawings in which like numerals indicate like parts throughout the several views, the numeral 40 5 designates generally the body of a consumer type container of the type with which this invention deals and which is characterized by the fact that it has a full opening top reinforced by a neck 6 and closed by a hinged cover 7.

45 In that embodiment of the invention shown in Figures 1 through 7, inclusive, the container is made from two separate pieces or units (Figures 4 and 5); the one shown in Figure 4 providing the back wall 8 of the container, the bottom wall 9 and the hinged cover 7, while the other unit shown in Figure 5 provides the front wall 10 and side walls 11.

50 As shown in Figure 7 the unit or piece providing the front and side walls is formed from

a blank which is vertically scored as at 12 to define the three panels which provide the front and side walls, and also vertical glue flaps 13 which extend for the full height of the blank. Across its bottom the blank is scored horizontally as at 14 to define bottom attaching flanges 15 on the front and side walls and also on the glue flaps 13, the strip providing these flanges being preferably diagonally scored as at 16 to facilitate the corner folds necessary to enable the flanges 15 to be turned in without requiring cutting the same at the corners.

Across its upper portion the blank shown in Figure 7 has three parallel spaced horizontal score lines 17, 18 and 19. These score lines define three parallel adjacent strips 20, 21 and 22 which are folded upon themselves to produce the neck 6. To obviate bunching of the material at the corners the strip 20 is cut out as at 23 adjacent to each corner defining score line 12.

As clearly shown in Figure 5 the strips 20, 21 and 22 which are of progressively greater widths are so disposed with respect to each other that the neck formed thereby is disposed inwardly of but parallel to the outer walls of the container. Thus, the strip 20 is bent down over the inner face of the front and side wall panels and the glue flaps 13, to all of which it may be adhered, if desired, and then the intermediate strip 21 is bent upwardly on the score line 18 to extend above the top of the body. Next, the third and final strip 22 is folded down over the inside face of the intermediate strip 21 and because of its greater width extends beyond or below the junction of the first and second strips defined by the score line 18 to overlie and be adhered to the adjacent inner faces of the front and side wall panels and the glue flaps 13.

Since the strips 20, 21 and 22 extend across the glue flaps 13 as well as the front and side wall panels the neck 6 formed thereby continues unbrokenly around all four corners of the container and extends across all but the back wall thereof.

The blank shown in Figure 6 from which the back and bottom walls and cover are formed is scored transversely or horizontally as at 24 and 25 to define the top and bottom edges of the back wall and provide the hinge about which the cover 7 swings. In addition this blank has two other transverse or horizontal scores 26 and 27 and vertical scores 28 in line with and forming extensions of the side edges of the back wall forming panel. These score lines 26, 27 and 28 define the top wall 29 of the cover and flange portions 30, 31 and 32 respectively at the back, front and side edges of the top wall.

In forming up the piece or unit shown in Figure 4 from the blank just described, the flanges 30, 31 and 32 are bent perpendicularly to the top wall portion 29 and secured together by the tongues 33 which in effect form extensions of the flanges 30 and 31 and which overlap and are adhered to the side flanges 32.

The two pieces or units are, of course, secured together by means of the glue flaps 13 which are adhered to the inner marginal edges of the back wall 8. After the two units or pieces are secured together, the resulting tube is slipped over an internal supporting mandrel 34 as shown in Figure 11 to support the cover 7 as it is formed, i. e. during the time the tongues 33 are adhered to the adjacent side flanges 32. The container is then stripped off the supporting mandrel and re-applied upside down as shown in Figure 12. This permits the bottom wall of the container to be likewise formed over an internal support and

which, as will be readily apparent, is effected by adhering the bottom forming flap 9 to the in-turned flanges 15.

This completes the container which then may be filled with the commodity for which it is designed and after it is full the cover is closed and sealed shut by applying a pressure sensitive strip 35 around the upper portion of the container as shown in Figure 2, or any other suitable manner of securing the cover closed may be employed.

In any event, upon removal of the sealing strip 35 or its equivalent the cover may be opened and reclosed at will.

Another embodiment of the invention is illustrated in Figures 8, 9 and 10. In this case the two piece construction just described is employed but the cover flanges are provided by a separate strip or piece 55 which is conveniently produced as part of the blank (shown in Figure 10) from which the front and side walls of the container are formed. In other words, the strip 55 before being severed from the body forming blank has its corner forming scores 56 formed therein at the same time the corner scores 12 are formed. At the same time the strip 55 is longitudinally scored as at 57 to enable the same to be bent to right angular shape in cross section and is diagonally scored as at 58 to allow folding over its horizontal flanges in the formation of the cover.

The manner in which the strip 55 is formed up and attached to the cover forming flap 29' is deemed obvious from the drawings, especially from Figures 8 and 9; and since the strip 55 is initially part of the body forming blank and is scored concomitantly therewith the cover will fit perfectly and its flanges will be absolutely flush with the front and side walls of the container. The neck 6' in this embodiment of the invention is produced in the same manner as that described in connection with Figures 1 to 7, inclusive.

From the foregoing description taken in connection with the accompanying drawings it will be readily apparent to those skilled in this art that this invention provides a consumer type container having many advantages over consumer type containers heretofore available, especially in view of the fact that the invention provides a full opening container which may have both top and bottom ends formed over an internal support and upon being opened by the consumer still has a convenient reclosable cover.

What I claim as my invention is:

1. A consumer type container having a tubular body comprising integral front and side walls and a separate back wall and having a flanged cap hinged to the back wall and which telescopes over a neck on the body, characterized by the fact that said neck comprises a plurality of parallel adjacent strips integral with the body walls with the exception of the back wall, the strip nearest the body walls being bent down from the upper edges thereof to overlie the inner faces of the body walls, the next adjacent strip being bent up from the bottom of the first strip and extending above the junction of the first strip with the body walls, and the next adjacent strip being bent down from the top edge of the second strip to overlie said second strip and extend therebeyond into overlying engagement with the body walls to which said last strip is adhered.

2. A consumer type container of the character described, comprising: a body having front, back, side, bottom and top walls, the front and side

walls being one integral piece, and the back, bottom and top walls being another integral piece; means securing the side marginal edges of the back wall to the adjacent edges of the side walls; means securing the bottom wall to the adjacent bottom edges of the side and front walls; a flange portion between the top wall and the back wall integral with both and defined therefrom by hinges; downwardly extending marginal flanges on the front and side edges of the top wall and with said flange portion at the back wall providing a continuous flange around the periphery of the top wall; and a neck protruding from the top of the body of the container, said neck having its lower portion anchored to the inner faces of the front and side walls and extending unbrokenly around all corners of the body and being snugly embraced by the marginal flanges of the cover when the cover is closed, said neck comprising a plurality of layers of the stock from which the front and side body walls are formed, integral with said body walls and folded from the upper marginal edge portions of said body walls to overlie the inner faces of said body walls and one another.

3. The consumer type container set forth in claim 2 further characterized by the provision of glue flaps extending along the rear edges of the side walls and adhered to the adjacent portions of the back wall to secure together the two pieces of which the container is made; and further by the fact that said neck extends across the glue flaps so that the perimeter of the neck is coextensive with the combined widths of said front and side walls and the glue flaps thereon.

4. The consumer type container set forth in claim 3 further characterized by the fact that said downwardly extending marginal flanges on the side and front edges of the top wall are formed from a piece initially separate from the top wall, which piece has a length equal to the width of the piece from which the front and side walls of the body and the glue flaps at the marginal edges of the side walls are formed, said strip being bent along a longitudinal fold line 45 into angular cross section and being bent transversely at the corners of the top wall and being adhered to the top wall.

5. A consumer type container of the character described comprising: a body having front, back, 50 side, bottom and top walls, the front and side walls being one integral piece and the back, bottom and top walls being another integral piece; means securing the side marginal edges of the back wall to the adjacent edges of the side walls; 55

means securing the bottom wall to the adjacent bottom edges of the side and front walls; a flange portion between the top wall and the back wall integral with both and defined therefrom by hinges; downwardly extending marginal flanges on the front and side edges of the top wall connected with said flange portion at the back wall to provide a continuous flange around the periphery of the top wall; and a neck protruding from the top of the body of the container and comprising a plurality of parallel adjacent strips integral with the body walls with the exception of the back wall, the strip nearest the body walls being bent down from the upper edges thereof to overlie the inner faces of the body walls, the next adjacent strip being bent up from the bottom of the first strip and extending above the junction of the first strip with the body walls, and the next adjacent strip being bent down from the top edge of the second strip to overlie said second strip and extend therebeyond into overlying engagement with the body walls, to which said last named strip is adhered.

6. In a consumer type container having side, front, back and bottom walls and a cover: a neck extending around the upper marginal edge portion of the front and side walls and comprising a narrow strip folded downwardly from the front and side walls and flatwise overlying the upper marginal edge portions thereof, a wider strip folded upwardly from the bottom of said narrow strip and flatwise overlying the narrow strip and extending thereabove, and a third strip, wider than said second designated strip and folded downwardly from the top thereof to overlie the same and extending therebelow, the portion of said third designated strip extending below the second designated strip being flatwise adhered to the inner surface of its adjacent wall; and downwardly extending flanges on the front and side edges of the cover for snugly telescoping over said neck.

LEWIS C. BROOKS.
